United States Patent Office

Des. 231,227
Patented Apr. 9, 1974

231,227

FAUCET SPOUT

Larry M. Hill, Frankfort, Ind., assignor to Indiana
Brass Company, Inc., Frankfort, Ind.

Filed Sept. 22, 1971, Ser. No. 182,924

Term of patent 14 years

Int. Cl. D23—01

U.S. Cl. D23—32

Fig. 1

Fig. 2

Fig. 3

Fig. 4

Fig. 5

FIG. 1 is an elevational view of a faucet spout showing my new design;

FIG. 2 is a top plan view thereof;

FIG. 3 is a bottom plan view thereof;

FIG. 4 is an end elevational view thereof; and

FIG. 5 is a perspective view thereof.

I claim:

The ornamental design for a faucet spout, substantially as shown.
